UNITED STATES PATENT OFFICE.

HOWARD D. COLMAN AND BURT A. PETERSON, OF ROCKFORD, ILLINOIS, ASSIGNEES TO
HOWARD D. COLMAN, LUTHER L. MILLER, AND HARRY A. SEVERSON, CO-PARTNERS
DOING BUSINESS AS BARBER-COLMAN COMPANY, OF ROCKFORD, ILLINOIS.

THREAD-BOARD-CLEANING APPARATUS.

1,137,305.

Specification of Letters Patent. Patented Apr. 27, 1915.

Application filed May 20, 1910. Serial No. 532,431.

To all whom it may concern:

Be it known that we, HOWARD D. COLMAN and BURT A. PETERSON, citizens of the United States, residing at Rockford, in the county of Winnebago and State of Illinois, have invented certain new and useful Improvements in Thread-Board-Cleaning Apparatus, of which the following is a specification.

In the operation of spinning, lint and dirt accumulate quite rapidly upon the thread-board. Such accumulation is objectionable for the reason that masses of lint sometimes drop onto the rotating bobbins and become entangled with the yarn being wound thereon, while in other instances the bunches of lint are spun into the yarn and cause the formation of gouts thereon. The usual method of cleaning the thread-board has consisted in wiping it by hand several times a day, using either a piece of waste or a small board covered with plush or some similar material. In order to clean the thread-board in this way, the spinning frame must be shut down, and consequently there is a loss of production during the cleaning operation. When cleaning the thread-board manually, a great many ends are usually broken down, which causes a further loss of production when the machine is started, and also results in the production of bad yarn due to the piecing-up of broken threads.

The object of this invention is to provide mechanical means for preventing the accumulation of lint and the like upon the thread-boards and thread-guides of a spinning frame.

In the accompanying drawings, Figure 1 is a top plan view of a spinning frame equipped with a cleaning apparatus embodying our invention, portions being broken away to shorten the view. Fig. 2 is a transverse vertical sectional view taken in the plane of dotted line 2-2 of Fig. 1. Fig. 3 is a sectional view through one of the traveling cleaning devices, showing also the thread-board and thread-guide, the view being taken on dotted line 3-3 of Fig. 4. Fig. 4 is a top plan view of the parts illustrated in Fig. 3. Fig. 5 is a rear end view of the cleaning device. Fig. 6 is a section on line 6-6 of Fig. 3. Fig. 7 is a section on line 7-7 of Fig. 4. Fig. 8 is a section on line 8 of

Fig. 3. Fig. 9 represents, in elevation, the devices for driving the cable that moves the cleaning devices. Fig. 10 is a view looking from the left hand side of Fig. 9. Fig. 11 illustrates a slack take-up for the cable. Fig. 12 is a view of the cable-driving mechanism. Fig. 13 is a section on line 13-13 of Fig. 12. Fig. 14 is a section on line 14-14 of Fig. 13. Figs. 15 and 16 are sectional views on line 15-15 of Fig. 13, showing the parts in two different positions. Fig. 17 is a section on line 17-17 of Fig. 12. Fig. 18 is a sectional detail of certain gears. Fig. 19 represents, in section, some of the parts of the cable-driving mechanism. Fig. 20 illustrates a clutch comprised in said mechanism.

We have herein shown the invention as adapted to a standard form of spinning frame, the apparatus being so arranged that no changes shall be necessary in the construction and arrangement of the parts of such frame. In Figs. 1 and 2, *a* are the drawing rolls, *b* the thread boards hinged to the frame, *c* the thread guides hinged to said thread boards, *d* the usual pit tails on the thread guides, *e* the separators, vertically movable in the spaces between the bobbins, *f* the longitudinal bars which carry said separators.

The cleaning apparatus comprises, in this instance, two devices 5 (Fig. 3) arranged to be reciprocated over the upper surface of the thread-boards and the thread-guides of the spinning frame. Said devices are herein shown, by way of example, as each comprising a roller 6 rotated through its contact with the thread-board as the device is traversed along said board, the roller having a peripheral flange 7 that rolls upon the thread-board. The roller 6 is of a generally conical form, the flange 7 being at the inner, larger end of the roller. In this instance, the roller is covered with a material 8 to which lint will readily cling, as, for example, plush. The roller is rotatably mounted upon a spindle 9 fixed to a plate 10, said plate having means to engage a cleaner-traversing device to be later herein described. Hinged to the plate 10 at 11 is a hood 12, adapted to inclose the upper part of the roller. The rear portions 12^a (Fig. 3) of the hood abut against the plate 10 and thus determine the operative position of the hood. The latter may be lifted by the op-

erative when the cleaner reaches the end of its reciprocatory travel, or at any other time, and the roller cleaned by grasping the roller and drawing off the lint clinging to the plush 8.

The two cleaning devices, one for each side of the frame, are attached to an endless cable 13 which is moved first in one direction and then in the other to traverse the 16 cleaning devices back and forth upon the thread-boards. The endless cable 13 is supported upon guide sheaves 14 so that opposite portions of the cables shall run longitudinally of the thread-boards and adjacent 15 to the inner edges of said boards and close to the frame of the machine.

At one end of the spinning frame and adjacent to one of the thread-boards is located the mechanism for driving the cable, for reversing its direction of movement, and for arresting its travel at certain times. The driving and reversing mechanism is inclosed in a housing 15 secured to the spinning frame at one end of one of the sets of drawing rolls. Rotatably supported in said housing is a shaft 16, one end of which projects outside of the housing and there carries a sheave 17 having two annular cable-receiving grooves therein. Attached to the spinning frame beneath the housing 15 is a vertically extending guide rod 18 upon which is slidably mounted a pulley block 19 weighted as indicated at 20 and containing a sheave 21 over which the cable 13 extends in passing 30 from one of the grooves in the sheave 17 to the other. The weighted sheave 21 serves as a tension device to take up the slack in the cable 13 and keep it taut at all times.

Power is communicated to the sheave 17 40 to drive the cable, from the shaft of one of the drawing rolls. On said shaft is fixed a pinion 22 meshing with a gear wheel 23 which is loose on a shaft 24 in the housing 15. The gear 23 has a clutch hub 25 (Figs. 45 and 20) adapted to coöperate with a clutch pin 26 fixed on a gear wheel 27, the latter gear being fast on the shaft 24. Loose on said shaft is a two-arm or bell-crank lever 28, one arm 28^a of which carries a gear 50 wheel 29, meshing at all times with the gear wheel 27. The other arm 28^b of the bell-crank lever supports two intermeshing gears 30 and 31, the gear 31 being in constant mesh with the gear 27. It will be seen that the gear 27 will drive the gears 29 and 30 in opposite directions. Said gears 29 and 30 are arranged to engage alternately with a gear 32 (Figs. 15 and 16) fixed on the shaft 16 that carries the cable-driving sheave 17, 60 whereby the cable is driven alternately in opposite directions. The bell-crank lever 28 is rocked to place the gears 29 and 30 alternately in mesh with the gear 32 by means comprising an arm 33 pivoted on the shaft 24 and connected to the arm 28^a by a tension

spring 34. Fixed in the lever 28 is a stop pin 35 to limit relative movement between said lever and the arm 33 in one direction. A stud 36 on the arm 33 is held against the periphery of a cam 37 by a torsion spring 38 surrounding the hub of the arm 33 and fixed at one end to said hub and at its other to a suitable fixed part, as 39. The cam 37 is operatively connected to the shaft 24 through a gear train 40 41 42 43 (Fig. 14). 70 As the cam 37 rotates, the arm 33 will be swung and the bell-crank lever 28 will be rocked to place the gears 29 and 30 alternately in mesh with the gear 32 to drive the cable in opposite directions. It will be understood that the springs 34 and 38 give the gears 29 and 30 an opportunity to mesh properly with the gear 32 should the latter of said gears happen not to mesh at the moment of contact. 80

As indicated in Figs. 2 and 3, the rollers 6 are of such length as to overlie and clean the thread-guides c. The cleaners are therefore of such length as to project into the region of movement of the separators e. The latter, as is usual, are fixed to bars f extending longitudinally of the spinning frame, said bars being vertically reciprocated by appropriate mechanism (not shown). If the traveling movement of the cleaners were continued after the separators e are raised far enough to extend into the spaces between the thread-guides c, the cleaners might collide with said separators. We therefore preferably provide means for arresting the 90 travel of the cleaners at the proper times to avoid interference with the separators, which means will be next described. 95

A rock shaft 44 (Figs. 12 and 17) mounted in the housing 15 has fixed thereto a lever 45 for shifting the gear wheel 23 into and out of clutch connection with the gear wheel 27. On one end of the shaft 44 is fixed an arm 46 (Fig. 10) having a stud 47 lying within a cam slot 48 in a cam 49 pivoted to the housing at 50. The cam 49 is rocked by an arm 51 connected by a link 52 to one arm of a lever 53 (Figs. 2 and 9). The lever 53 is pivoted upon a pin 54 adjustably fixed in a bracket 55 attached to the spinning frame. 110 The other arm of said lever carries a weight 56 and extends into the path of movement of one of the bars f. As the bars f are raised, the adjacent bar tilts the lever 53, thereby operating the lever 45 to disconnect the gear 23 from the shaft 24, and stopping the cleaning apparatus. When the separators e have descended below the plane of the thread-guides c, the weight 56 operates the shifting lever 45 to drive the cable 13. 53^a (Fig. 9) 115 is an adjustable stop to limit the starting movement of the lever 53. 120

The cleaners 5 may be connected to the cable 13 by any suitable means, but preferably a yielding connection is used, that here- 130

in shown consisting of clip 57 formed on the plate 19 and embracing the cable, and fingers 58 also formed on said plate and lying at one side of the cable. The cable is held by the clip 57 and fingers 58 with sufficient force to cause the cleaner to move with the cable, unless the cleaner should meet with some obstruction, when the cable slips through said clip.

10 The yielding connections between the cleaners and the cable are provided because stoppage of the cleaners by reason of temporary obstruction is not infrequent and in order that the cleaners shall certainly 15 traverse the entire length of the thread-boards, notwithstanding such stoppages, the reversing mechanism for the cable is so proportioned as to allow the cable to run in each direction for a longer period of time

20 than is necessary to move the cleaners the entire length of the thread-boards. When the cleaners reach the ends of their respective thread-boards, the cleaners are arrested by reason of contact with steps which may 25 consist of hooks 59 through or past which the cable runs. During the overrunning of the cable, the clip 57 and fingers 58 slip on the cable.

30 In operation, the cable is caused to traverse the cleaners 5 back and forth over the thread-boards and the thread-guides. As the rollers 6 roll along the thread-boards and guides lint and dirt lying upon said boards and guides cling to the plush-covered surface of the rollers. When the rollers reach 35 the ends of the frame, or at any other convenient time, the operator lifts the hooks 12, grasps the rollers and strips off the lint and dirt.

40 As hereinbefore described, the travel of the cleaners 5 is automatically arrested when the separators 6 rise above the plane of the thread guides.

The form and dimensions of the cleaners 45 are such that they may travel over the thread-boards and guides beneath the yarn running from the drawing rolls to the pig-tails 4 without interfering with said threads.

50 The cleaners 5 tilt upwardly with the thread boards when the latter are thrown back preparatory to the doffing operation.

By the use of the apparatus herein described the thread boards and thread guides are kept clear of lint and dirt, thereby preventing the formation of knots in the yarn, and eliminating the loss of production due 55 to stoppage of the frame for the usual manual cleaning and the piecing-up of ends broken down during such hand operation.

60 It will be seen that an apparatus embodying our invention may be installed upon a standard spinning frame without making any alterations in the latter. The driving, reversing, stopping and driving mechanism is contained into a compact, unitary structure

which may easily be attached to the frame in position for actuation by an element (22) present in the standard frame. The slack take-up and the device for controlling the starting and stopping clutch are of such form that they may be conveniently arranged beneath the housing 15. The cable 13 is carried by guide sheaves 14 which may be easily mounted upon the frame.

It will be noted that the cleaner 5 does not push the lint ahead of it, but instead the lint is rolled upon the plush-covered roller, and becomes temporarily attached to it, and is not liable to displacement. The hook 12 prevents the lint carried by the roller from coming in contact with the cleaner.

There is but one cord or cable beneath the drawing rolls at each side of the machine. It lies close to the frame of the machine, and in no way interferes with the removal of the scavenger rolls, nor prevents easy access to the space behind the rolls for cleaning purposes.

The invention is not limited to the details herein described, for various modifications will occur to persons skilled in the art.

We claim as our invention:

1. The combination of a spinning frame, a thread-board hinged at one edge to said frame for swinging upwardly, a series of thread-guides attached to the other edge of the thread-board, a cable supported for movement longitudinally of the frame and close to the hinge connection between the frame and the thread-board, means for moving the cable, a plate attached to said cable for swinging movement in a vertical plane, a spindle fixed to the forward side of said plate, a tapering roller mounted on said spindle and overlying the thread-board and thread-guides, said roller having a surface to which lint will cling, and a hood for the roller, said hood being hinged to said plate, said plate, spindle, roller and hood being capable of swinging upward with the upward swinging movement of the thread-board.

2. In a spinning machine, a part to be cleaned, a device for cleaning said part, means for moving said device along said part, separators movable in the operation of the spinning frame into the path of movement of said cleaning device, and means for suspending the operation of said cleaner-moving means.

3. In a spinning machine, a part to be cleaned, a device for cleaning said part, means for moving said device along said part, separators movable in the operation of the spinning frame into the path of movement of said cleaning device, and means automatically actuated by the upward movement of said separators for suspending the operation of said moving means.

4. In a spinning machine a part to be cleaned, a device for cleaning said part, means for moving said device along said part, separator means movable in the operation of the spinning frame into the path of movement of said cleaning device, and a lever and connections for starting and stopping said cleaner-moving means, said lever being arranged to be engaged by said separator means.
5. In a spinning machine, a thread-board, thread-guides attached to said thread-board, a device for cleaning said thread-board and thread-guides, means for moving said device along the thread-board and thread-guides, a vertically-reciprocating bar extending longitudinally of the spinning machine, separators attached to said bar and movable vertically through the spaces between the thread-guides, and means actuated by said bar for controlling the operation of said moving means.
6. In a spinning machine, a thread-board, thread-guides attached to said thread-board, a device for cleaning said thread-board and thread-guides, means for moving said device along the thread-board and thread-guides, a vertically-reciprocating bar extending longitudinally of the spinning machine, separators attached to said bar and movable vertically through the spaces between the thread-guides, a lever and connections for starting and stopping said cleaner-moving means, said lever being arranged to be engaged and moved by said bar in the upward movement of the latter, and means for restoring said lever to its normal position upon the downward movement of said bar.
7. In a spinning machine, a thread-board cleaner, a cable for traversing said cleaner along the thread-board, means for driving said cable, said means including a clutch, a lever pivoted in the machine, connections between one arm of said lever and said clutch, separator means arranged to move the other arm of said lever in the direction to throw out the clutch, and means for swinging said lever arm to throw in the clutch.
8. A lint-collecting roller for thread-board cleaning apparatus having a tapering body, with a peripheral supporting flange adjacent to the larger end of the roller, the tapering surface of said roller being covered with material to which lint will cling.
9. In a spinning machine, drawing rolls; a thread-board; an endless cable; a cleaning device attached to said cable to travel therewith over said thread-board; means for driving said cable; means for reversing the direction of movement of said cable; and a housing in which said driving and reversing means are compactly mounted, said housing being mounted at one end of the drawing
- rolls and said driving mechanism being actuated from the shaft of one of the drawing rolls.
10. In a spinning machine, drawing rolls; a thread-board; an endless cable; a cleaning device attached to said cable to travel therewith over said thread-board; means for driving said cable; means for reversing the direction of movement of said cable; a housing in which said driving and reversing means are mounted, said housing being mounted at one end of the drawing rolls; and a slack take-up for said cable, said take-up being mounted directly beneath said housing.
11. In a spinning machine, drawing rolls; a thread-board; a separator-carrying bar; an endless cable; a cleaning device attached to said cable to travel therewith over the thread-board; means for driving said cable; means for reversing the direction of movement of said cable; a housing in which said driving and reversing means are mounted, said housing being mounted at one end of the drawing rolls; and means arranged for engagement by the separator-carrying bar for controlling the operation of said driving means.
12. In a spinning machine, drawing rolls and a thread-board at each side of the machine, a single endless cable extending along both sides of the machine and close to the thread-boards, a housing attached to the spinning machine at one end of one of the sets of drawing rolls, cable driving and reversing mechanism located in said housing and driven from the shaft of one of said drawing rolls, and cleaning devices attached to the cable for cleaning the thread boards.
13. In a spinning machine, a hinged thread-board, thread guides attached to the front edge of said thread-board, a cable having a portion supported to move parallel with and close to the axis of pivoted movement of the thread-board, a support attached to said cable-portion, a roller rotatably connected to and extending forwardly from said support, said roller having a surface to which lint will cling and being of sufficient length to extend across the thread-board and the thread-guides and being tapering so as to extend close to the spinning yarn without interference with the latter, a cover for the upper side of the roller conforming substantially to the shape of the roller and hinged to said support, said roller and cover being arranged to tilt upwardly substantially on the axis of said cable-portion when the thread-board is thrown back, and means for operating the cable.
14. The combination of a thread-board, a cable supported for movement along the thread-board, a cleaner having a yielding connection with the cable to allow the cleaner to slip on the cable; means for driv-

ing said cable; means for reversing the direction of movement of the cable; and means at each end of the thread-board for arresting the travel of the cleaner.

- 5 15. The combination of a frame, a thread-board hinged at one edge to the frame for upward swinging movement, an endless cable extending along the thread board close to the hinged edge thereof, a cleaner having 10 at its inner end a frictional engagement with the cable capable of allowing the cleaner to

slip on the cable, said cleaner being arranged to clean the thread-board; means for driving the cable in opposite directions; and means at each end of the thread-board for 15 arresting the travel of the cleaner.
